COMBINATION DRINKING GLASS AND DISH HOLDER

Lester W. Van Haften and George D. Hanby,
Chicago, Ill., assignors to Walgreen Co.,
Chicago, Ill., a corporation of Illinois

Application January 5, 1946, Serial No. 639,441

3 Claims. (Cl. 248—146)

1

This invention relates to receptacle holders and more particularly to a combination drinking glass and dish holder, although certain features thereof may be employed with equal advantages for other purposes.

It contemplates more especially a simple and improved holder that can be utilized in one or more positions to support a drinking glass or dish to effectively present such as a utensil which aids in the consumption of the contents of the supported receptacle.

It is advantageous and desirable to provide a standard holder for the various receptacles that are utilized in over-the-counter vending of liquids and solids such as sodas, sundaes, and ice cream constituting the primary fountain dispensing substances. It is customary to provide separate drinking or soda glasses as well as dish holders to the end that a supply of each must be maintained, and these require cleansing to the end that the proper type is not always available or conveniently at hand. With the provision of a combination drinking or soda glass as well as dish holder, there is no such problem entailed, with the result that the vending of these fountain commodities will be hastened and accomplished with greater efficiency.

One object of the present invention is to provide an improved combination drinking glass and dish holder to enable the more effective vending of fountain commodities.

Another object is to provide a simple, compact, and improved combination glass and dish holder that can be utilized in one of two positions to effectively support either type of receptacle.

Still another object is to provide an improved receptacle holder which has the ends thereof so arranged to serve either as a base or holder for various types of receptacle.

A further object is to provide an improved receptacle holder that renders itself to the combination of different types of utensils by merely changing its supporting position.

A still further object is to provide a double ended holder that can be alternately used as a support for drinking or soda glasses and dishes to effectively present such as utensils in the vending of fountain commodities.

Still a further object is to provide a combination handle holder than can be utilized as a support for different types of fountain utensils of the receptacle type.

Other objects and advantages will appear from the following description of an illustrated embodiment of the present invention.

2

In the drawing:

Figure 1 is a front view in elevation of a receptacle holder embodying features of the present invention, it being illustrated in a position for holding and supporting a drinking or soda glass receptacle.

Figure 2 is a top plan view of the holder and receptacle shown in Figure 1.

Figure 3 is a fragmentary sectional view taken substantially along line III—III in Figure 2.

Figure 4 is a fragmentary sectional view in elevation of the holder shown in a comparable inverted position to that shown in Figure 1, with the holder serving to support a dish.

Figure 5 is a top plan view of the holder and receptacle shown in Figure 4.

The structure selected for illustration is not intended to serve as a limitation upon the scope or teachings of the invention, but is merely illustrative thereof. There may be considerable variations and adaptations of all or part of the teachings depending upon the dictates of commercial practice.

The present embodiment comprises a substantially frusto-spherical body 10 stamped, molded or otherwise shaped from metallic, plastic, or other suitable material to present an enlarged peripheral base 11. The peripheral base 11 has a rounded edge 12 defined by an inwardly turned peripheral edge 13 to reinforce the body 10 along the base edge 12 thereof. The orifice or opening defined by the inwardly turned flange 13 of the body member 10, is sufficiently large to frictionally receive the base 14 of a saucer-type dish 15 which may advantageously be used for the reception and support of a plurality of one or more scoops of ice cream therein. The dish 15 is separate and distinct from the holder 10; however, the former is readily associative and removable relative to the concave interior 16 of the holder 10. The concave interior 16 of the holder 10 communicates with a peripheral vertical flange 17 defining the smaller orifice or opening compared to the larger base opening 13 of the holder 10.

The flange 17 defines a circular orifice sized to conform with and to frictionally receive the base 18 of a drinking or soda glass 19. The drinking or soda glass is preferably though not essentially of frusto-conical configuration proximate to the lower region thereof to present a tapered lower region 20 compared to the upper region 21 which may be of any desired shape or configuration depending upon the dictates of commercial practice. In order to effectively hold and

support a drinking or soda glass base 18 in the body 10, the flange defining orifice 17 is also slightly tapered to conform with the exterior drinking glass base 18 to provide a supporting surface therefor.

The tapered drinking glass base supporting orifice 17 aligns and cooperates with a proportionately shaped tapered ring 22 that is in vertical parallel spaced relation therewith to telescopically receive the lower tapered glass region 10 of the drinking glass 19 therethrough with the lower base 18 thereof received and supported in the smaller holder orifice 17. This effectively supports the glass in a vertical upright position (Figures 1 and 3) by reason of the fact that the auxiliary glass supporting ring 22 is maintained in parallel spaced relation with the holder body 10 by means of a plurality of radially extending and depending arms 23-24-25, in this instance three, that extends between the holder body 10 and the ring 22 for rigid support of the latter relative to the former.

In the present embodiment, the arms 23-24-25 are substantially L-shaped to present terminals 26-27 complementary to the convex exterior of the holder body 10 and the ring 22, respectively. The arms 23-24-25 may be formed integral or separate from the holder body 10 and ring 22 for uniform circumferentially spaced connection therewith to serve the dual purpose of a finger grasping expedient and also to support the ring 22 in rigid aligned parallel spaced relation with the holder body orifice 17. The arms 23-24-25 and their shorter legs 28 radially disposed in the plane of the drinking glass supporting ring 22 to cooperate therewith and serving as a base to support the holder body 10 in its position when utilized to hold a dish or other similar receptacle 85 in an upright position (Figure 4).

When reversed so that the larger orifice 13 of the holder body 10 is downward (Figure 1) to usefully serve as a base supporting peripheral edge 12, a drinking or soda glass 19 can be inserted for reception and support between the holder orifice 17 and the spaced auxiliary ring 22 to effectively retain a drinking type of glass in an upright position for manipulation by the arms 23-24-25. It will be observed, therefore, that the holder 10 has its ends 12-28 alternately serve as supporting bases with their respective orifices 13-22 serving as utensil supporting expedients so that a common holder may be utilized for different types of receptacles presented as containing utensils for fountain-vended commodities and the like.

While the number or shape of the arms 23-24-25 may be varied within a wide range depending upon the dictates of commercial practice and this is similarly true of the shape and configuration of the holder body 10, yet the dual purpose holder is uniquely adapted to fountain use by reason of its universal application to receptacles of varied types that are utilized in fountain vending of commodities.

While we have illustrated and described a preferred embodiment of this invention, it must be

understood that the invention is capable of considerable variation and modification without departing from the spirit of the invention. We, therefore, do not wish to be limited to the precise details of construction set forth, but desire to avail ourselves of such variations and modifications as come within the scope of the appended claims.

We claim:

1. A receptacle holder comprising a body member having aligned oppositely extending openings for alternate use as a receptacle and supporting base, said openings being variously sized to accommodate a dish base in the larger one and a drinking glass base in the smaller one, handle arms extending from said body member and beyond said smaller opening therein, and a ring member supported by said arms in axial alignment with the smaller opening in said body member to cooperate therewith in supporting a drinking glass therebetween.

2. A receptacle holder comprising a body member having opposed openings, said openings being variously sized to accommodate a dish base in the larger one and a drinking glass base in the smaller one, substantially L-shaped handle arms extending from said body member and beyond said smaller opening therein, and a ring member supported by said arms in axial alignment with the smaller opening in said body member to cooperate therewith in supporting a drinking glass therebetween, said L-shaped arms having straight portions adjacent said ring to extend the base supporting surface thereof.

3. A receptacle holder comprising a frusto-convex body member having opposed openings, said openings being variously sized to accommodate a dish base in the larger one and a drinking glass base in the smaller one, substantially L-shaped handle arms extending from said body member and beyond said smaller opening therein, and a frusto-conical ring member supported by said arms in axial spaced parallel alignment with the smaller opening in said body member to cooperate therewith in supporting a drinking glass therebetween, said L-shaped arms having straight portions adjacent said ring to extend the base supporting surface thereof.
